UNITED STATES PATENT OFFICE.

EDWARD WILLIAM KERNER, OF ERIE, PENNSYLVANIA.

FENCE-POST.

No. 866,478.

Specification of Letters Patent.

Patented Sept. 17, 1907.

Application filed November 20, 1906. Serial No. 344,277.

To all whom it may concern:

Be it known that I, EDWARD WILLIAM KERNER, a citizen of the United States, residing at Erie, in the county of Erie, State of Pennsylvania, have invented 5 certain new and useful Improvements in Fence-Posts; and I do hereby declare the following to be a full, clear, and exact description of the invention, such as will enable others skilled in the art to which it appertains to make and use the same.

10 It is the object of this invention to provide a fence post of malleable or gray iron or other suitable metal for the support of a plain or barbed wire fence, the post being constructed so as to sit firmly in the ground and be stiff and steady to a degree that fewer posts of the 15 structural character of this invention may be needed than posts as commonly formed.

The nature of the invention is readily ascertained from the device portrayed in the annexed drawings, forming a part of this specification, in view of which the 20 improvements will first be described with respect to their construction and mode of use, and then be pointed out in the subjoined claims.

Of the drawings—Figure 1 is a front elevation of the improved post complete. Fig. 2 is a rear elevation. 25 Fig. 3 is a side elevation. Fig. 4 is a transverse section. Fig. 5 is a view of a portion of the edge of the post showing the manner of “stapling” the fence thereto.

Similar numerals of reference designate similar parts or features, as the case may be, wherever they occur. 30 In the drawings 10 designates the post which may be composed of gray or malleable iron or other suitable metal, and which, from the base to the top may, for example, be eight feet in length; and, supposing three feet to extend into the ground, it will be five feet above 35 the surface of the latter.

The body of the post tapers on sides from the ground line to the top and its edges 13 are thinned down to some extent and in the margin of the edges there are lines of perforations 14 which extend from the top to the 40 bottom part of the post on each side, said perforations being made for the reception of staples 15 passed at their ends through the perforations 14 and their ends

clenched on the inner side to hold the line wires 16 closely secured to the front face of the post which is flat so as to have the fence extend therealong without interruption. The post described has an outwardly projecting rib 17 which extends centrally from the back of the post and from top to bottom thereof. The outer margin 18 of the said rib 17 is also provided with perforations 14 so that the end of a fence extending at right angles to a fence secured to the face of a post may be attached to the margin of the said rib. A slot or notch, 19, is made in the post near the top for use in fastening an extraordinary strong truss wire to the post in case an unusually high fence is secured to the posts, and in view of this 55 contingency the perforations 14 in the margins of the sides and edge of the rib are made through the post from top to bottom, in order that the post when set in the ground to an extent less than three feet may be used to have a fence of greater height than the five feet secured 60 to the said post in the manner explained.

Under the construction specified, a highly serviceable and durable post is secured, and one that while simple in construction is adapted to meet substantially 65 all exigencies in the construction of a wire fence.

What is claimed is—

A fence-post composed of metal provided with anchoring means at its base, and having a flat front face with thinned edges, and perforations at short intervals through the margins of the said thinned edges, said perforations extending from the top to the bottom of the post, and the latter being furthermore provided on its back with a rib extending back at a right angle to the plane of the face of the post, said rib being thinned or reduced at its outer edge and perforations formed at short intervals through the said thinned edge whereby a line of fence may be secured to the face of the post and extend in the plane of the same and the end of another line of fence may be connected to the rib and extend at a right angle to the first-mentioned line of fence.

In testimony whereof, I affix my signature, in presence of two witnesses.

EDWARD WILLIAM KERNER.
